UNITED STATES PATENT OFFICE

112,871

DESIGN FOR A SANDING TOOL UNIT

Eugene Balough and Michael J. Yamen,
Poughkeepsie, N. Y.

Application November 17, 1937, Serial No. 72,957

Term of patent 3½ years

To all whom it may concern:

Be it known that we, Eugene Balough and Michael J. Yamen, citizens of the United States of America, residing at Poughkeepsie, in the county of Dutchess and State of New York, have invented a new, original, and ornamental Design for a Sanding Tool Unit, of which the following is a specification, reference being had to the accompanying drawing, forming part thereof.

We claim:

The ornamental design for a sanding tool unit, as shown.

EUGENE BALOUGH.
MICHAEL J. YAMEN.
